UNITED STATES PATENT OFFICE

2,472,531

PANORAMIC RECEIVER WITH PULSE
NARROWING SYSTEMSJoseph I. Heller, New York, N. Y., assignor to
Panoramic Radio Corporation, New York, N. Y.,
a corporation of New York

Application May 7, 1946, Serial No. 667,847

3 Claims. (Cl. 250—20.)

1

This invention relates generally to pulse narrowing and sharpening, having particular but not exclusive application to panoramic equipment.

In displaying pulses on oscilloscopes and the like, the indication provided in response to a peaked signal possesses an outline determined only in part by the character of the signal, a factor of equal importance with the character of the signal being the character of the circuits which translate the signal between its point of origin and the deflection producing elements of the cathode-ray tube.

In particular, in connection with panoramic technique, a substantially single signal frequency normally produces an indication on the face of the indicator determined primarily by, and corresponding substantially with, the frequency characteristic of the intermediate frequency amplifier of the panoramic device, since the signal is frequency swept during its translation in the panoramic device, through the pass band of a translating channel.

It is desirable, in connection with panoramic technique in particular, and in oscilloscope design generally, to provide means for sharpening or narrowing indicated pulses in order to enable discrimination between adjacent pulses, to enable accurate interpretation of the indications and of their location on the face of the indicator.

I provide means for narrowing pulses, in accordance with a novel principle, to wit, by passing each pulse in parallel through a pair of I. F. channels, one of which has low Q, and the other of which has high Q, and detecting the outputs of the I. F. channels in polarity, opposing relation, to provide a narrowed pulse, the rationale of the method involving the well known property of tuned circuits, that such circuits of radically different Q are at and adjacent to the edges of the pass bands thereof substantially similar.

It is, accordingly, an object of my invention to provide devices for narrowing pulses.

It is a further object of my invention to provide panoramic displays providing pulses which are narrower and sharper than has hitherto been the case.

It is still another object of my invention to provide for narrowing pulses by a comparison method, the pulses being passed in parallel through translating circuits having radically different gains at the center and substantially similar gains adjacent the edges of their characteristics.

The above and still further objects and advantages of my invention will become clear upon

study of the following detailed description of a specific embodiment of the invention, when taken in conjunction with the accompanying drawings, wherein:

5. Figure 1 is a block circuit diagram of an embodiment of my invention; and

Figure 2 is an illustration of certain frequency characteristics associated with the embodiment of Figure 1, and indicating the character of responses available in apparatus utilizing my invention.

Referring now to the drawings, the numeral 1 denotes an antenna, for providing signals to the wide band R. F. amplifier 2, the amplified R. F. signals being applied to a mixer 3 for conversion to a suitable I. F. frequency, in the manner well known per se in the radio art, by applying to the mixer 3 a signal derivable from the local oscillator of the frequency of the local oscillator 4. The frequency of the local oscillator 4 is swept through a predetermined frequency spectrum by means of a reactance tube 5, to which may be supplied control potentials, preferably of sawtooth character, and provided by the sawtooth oscillator 6.

The circuit arrangement above described in detail is old and well known per se, in the art, relating to panoramic receiving and analyzing devices, and is intended to be exemplary only of many similar devices, to which my invention may apply. The above described circuit, and still further circuits for the same purpose, and to which my invention is applicable, have been described in the U. S. patent to Wallace et al., No. 2,381,940, issued August 14, 1945, on the basis of an application Serial No. 402,822, filed July 17, 1941, and in the U. S. patent to Marcel Wallace No. 2,367,907, issued January 23, 1945, on the basis of an application Serial No. 420,014, dated November 21, 1941.

The signal derived from the mixer 3 may be applied to a pair of I. F. channels 7 and 8, connected in parallel, the channel 7 being arranged and adapted to have relatively low Q, and the channel 8 to have relatively high Q. The outputs of the I. F. channels 7 and 8 are applied respectively to the plates 9 and 9a of rectifier tubes 10 and 11, the respective cathodes 12 and 13 of the tubes 10 and 11 being connected in series with a pair of resistors 14 and 15, the midpoint 16 of which may be grounded. The algebraic sum of the rectified voltages provided across each of the resistors 14 and 15 is available at the cathodes 12 and 13, which may accordingly be connected to the vertical plates 17 of a cathode-ray oscil-

loope 18, a horizontal plate 19 of which is grounded, and the other horizontal plate of which may be connected to the sawtooth generator 6 which provides sweep voltage for the indicator 18.

As the local oscillator 6 is swept through its assigned frequency spectrum, signals available in the wide band R. F. amplifier 2 are brought successively to edges of the pass bands of the channels 7 and 8, and then swept through the said pass bands, producing thereby signals of varying amplitude corresponding with the transfer impedance characteristics of the channels 7 and 8, respectively, and which are illustrated at 20 and 21, respectively, in Figure 2 of the accompanying drawings. The curve 20 represents the characteristic of a heavily loaded tuned circuit, of low Q, and the curve 21 that of a lightly loaded, or high Q tuned circuit.

The signal appearing across the deflection plates 17 of the indicator 18 has ordinates corresponding with the difference between the ordinates of the curves 20 and 21, for each point on the frequency or time axis. The signal 22 may be amplified, if desired, prior to application to the plates 11. Since the above described action takes place for weak as well as for strong signals, small signals are not differentiated against by my novel method of narrowing the visible width of signal indications.

It will be clear that my invention may be applied to double conversion panoramic devices, such as is illustrated in Figure 1 of Wallace et al., #2,381,940, referred to supra, by utilizing two parallel 2nd I. F. channels, each having a different relative Q. It will further be clear that my invention may be applied to panoramic devices comprising no conversion step, and no I. F. channels, and which may be of the character illustrated in Figures 1 or 4 of the patent to Wallace, No. 2,367,907, referred to supra, by utilizing a pair of video amplifiers in parallel, each having a different relative gain at the center of its pass band and similar gains at the edges of its pass band.

I do not, however, intend to limit my invention to application in any of the above panoramic devices, since it will find application to devices of various character in which panoramic principles are employed, or in which frequency modulated signals are visually indicated, or in which signals generally are indicated in the face of an oscilloscopic indicator.

Having described various specific embodiments of my invention, I desire to point out that various modifications thereof may be resorted to without departing from the spirit of the invention.

What I claim and desire to secure by Letters Patent of the United States is:

1. In a panoramic receiving system for analyzing signals occupying a first predetermined frequency spectrum, means for converting said signals to further signals occupying a second predetermined frequency spectrum, said last named means comprising a local oscillator for generating a heterodyning frequency, means for periodically varying said heterodyning frequency, a first narrow band intermediate frequency tuned channel coupled with said means for converting said signals to translate succeeding selected portions of said second predetermined frequency spectrum in time sequence during periodic variation of said heterodyning frequency, said first intermediate frequency channel having a predetermined high ratio of peak response to response at high energy points of the selectivity characteristic thereof, means comprising a further tuned intermediate

frequency channel coupled with said means for converting said signals to translate selected portions of said second predetermined frequency spectrum in time sequence during periodic variation of said heterodyning frequency, said further intermediate frequency channel having a predetermined low ratio of peak response to response at half energy points of the selectivity characteristics thereof, said first and further intermediate frequency channels being tuned to the same center frequency, and having substantially identical responses at a plurality of points below said first mentioned half energy points, means for separately detecting signals translated by said first and further intermediate frequency channels, means for differentially combining the outputs of said means for separately detecting, a cathode ray tube indicator having a cathode ray beam and means for deflecting said cathode ray beam in a first and a second coordinate direction, means for controlling said means for deflecting to deflect said cathode ray beam in said first coordinate direction in synchronism with variations of said heterodyning frequency and means responsive to said means for differentially combining for controlling said means for deflecting to deflect said cathode ray beam in said second coordinate direction.

2. A spectrum analyzer for analyzing a band of discrete signals occupying a predetermined wide frequency spectrum, a first relatively narrow band frequency amplifier having a relatively great selectivity, a second relatively narrow band frequency amplifier having a relatively low selectivity, means for applying said band of discrete signals to said first and second amplifiers in parallel, means for periodically and continuously frequency scanning said band of discrete frequencies with respect to said first and second amplifiers, whereby each signal of said band of signals scans periodically through the selectivity characteristics of said first and second amplifiers, means for detecting the amplified output of said first amplifier, means for detecting the amplified output of said second amplifier, means for differentially combining said detected outputs, a visual indicator for displaying the frequency content of said band of discrete signals, and means responsive to said means for differentially combining for activating said visual indicator to provide a distinctive visual response for each signal of said band of discrete signals.

3. In combination, in a system for analyzing a band of signals distributed within a predetermined frequency spectrum, a local oscillator for providing heterodyning signals, a mixer for converting said frequency spectrum to a further frequency spectrum by combining said signals with said heterodyning signals, means for amplifying a selected portion only of said further frequency spectrum, means for periodically varying the frequency of said local oscillator to vary periodically said selected portion of said further frequency spectrum, said means for amplifying comprising a pair of tuned circuits connected with their inputs in parallel, said tuned circuits having one a high Q and the other a low Q and being both tuned to the same resonant frequency, Q meaning the ratio of reactance to resistance of the tuned circuit at resonant frequency, separate means for detecting the responses of said tuned circuits to signals applied thereto, means for differentially combining said detected responses, and means responsive to said means for differentially combining for visually plotting said responses for all

signals of said band of signals simultaneously against a frequency base line.
